The ornamental design for a handle for mesh basket, as shown and described.

DESCRIPTION

FIG. 1 is a front perspective view of a first embodiment of a handle for mesh basket showing our new design;

FIG. 2 is a front view thereof;

FIG. 3 is a left side view thereof, the right side being a mirror image;

FIG. 4 is a front perspective view of a second embodiment thereof;

FIG. 5 is a front view thereof;

FIG. 6 is a left side view thereof, the right side being a mirror image;

FIG. 7 is a front perspective view of a third embodiment thereof;

FIG. 8 is a front view thereof; and,

FIG. 9 is a left side view thereof, the right side being a mirror image.

The broken line showing of structural lines is included for the purpose of illustrating non-claimed subject matter and forms no part of the claimed design. The dash-dot broken lines represent an artificial boundary and form no part of the claimed design. The mesh material that may be visible through the holes in the mesh has been removed for clarity.
